UNITED STATES PATENT OFFICE

166,852

COMBINATION PHONOGRAPH, RADIO, AND TELEVISION RECEIVER CABINET

Jack De Young, Grand Haven, Mich., and Thorvald Petersen, Skokie, and Herbert H. Steglich, Wilmette, Ill., assignors to Zenith Radio Corporation, a corporation of Illinois

Application December 4, 1951, Serial No. 17,606

Term of patent 7 years

(Cl. D56—4)

To all whom it may concern:

Be it known that we, Jack De Young, a citizen of the United States, residing at Grand Haven, in the county of Ottawa, State of Michigan, Thorvald Petersen, a citizen of the United States, residing at Skokie, in the county of Cook, State of Illinois, and Herbert H. Steglich, a citizen of the United States, residing at Wilmette, in the county of Cook, State of Illinois, have invented a new, original, and ornamental Design for a Combination Phonograph, Radio, and Television Receiver Cabinet, of which the following is a specification, reference being made to the accompanying drawings forming a part thereof:

Figure 1 is a perspective view of a combination phonograph, radio, and television receiver cabinet embodying our new design with the phonograph and radio compartments closed, and

Figure 2 is a perspective view of the cabinet with the above-mentioned compartments open.

The side of the cabinet not shown is the same as the side shown, and the top and rear of the cabinet are plain. The entire grille area of the cabinet is covered with fabric.

We claim:

The ornamental design for a combination phonograph, radio, and television receiver cabinet, substantially as shown and described.

JACK DE YOUNG.
THORVALD PETERSEN.
HERBERT H. STEGLICH.
